UNITED STATES PATENT OFFICE.

CHARLES H. SEMPLE, OF TRENTON, NEW JERSEY.

DESIGN FOR A RESILIENT TIRE.

43,438.

Specification for Design.

Patented Jan. 7, 1913.

Application filed July 16, 1912. Serial No. 709,826. Term of patent 14 years.

To all whom it may concern:

Be it known that I, CHARLES H. SEMPLE, a citizen of the United States, residing at Trenton, in the county of Mercer and State of New Jersey, have invented a new, original, and ornamental Design for Resilient Tires, of which the following is a specification, reference being had to the accompanying drawings, forming part thereof, in which—

Figure 1 is a plan of a portion of a resilient tire suitable for use on an automobile, showing my new design; and Fig. 2 is a side elevation thereof.

Referring to the drawings, the longitudinally and transversely curved surface of the tire 1 is provided with a series of hollow or skeleton triangles 2 whose apices are best somewhat rounded as shown, and whose sides are formed by raised ribs molded in the tread material. Located centrally of the hollow or depression bounded by the

sides of each raised triangle is a projecting circular stud 3. The triangles, which are substantially equilateral, are arranged in series around the entire tire periphery or tread with a median line of each lying transversely of the tread, and the arrangement is such that along each side of the tread the triangle apices and bases or sides alternate. Each triangle is spaced away from that on either side of it, and the adjacent sides of any two adjoining triangles are substantially parallel. Ribs 4 extend continuously around the tire and constitute bounding or limiting ribs for the tread surface.

I claim:

The ornamental design for a resilient tire as shown and described.

CHARLES H. SEMPLE.
